UNITED STATES PATENT OFFICE.

RICHARD C. DAVIS, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

Application filed May 5, 1924. Serial No. 711,034.

This invention relates to telephone exchange systems and more particularly to common battery systems in which connecting circuits are used in extending calls from a calling to a called line.

The object of this invention is to provide an improved and simplified connecting circuit for such systems by means of which the service is greatly improved.

10 One of the features of the invention is the provision of a simplified connecting circuit of the above character whereby the application of ringing current to the called line is interrupted should the calling subscriber 15 replace his receiver prior to receiving a response from the called substation.

Another feature of the invention resides in the provision of means whereby when the receiver at the calling station has been restored and subsequently removed from the switchhook, a circuit interrupting device is brought into operative relation with a supervisory signal to cause said signal to flash in a characteristic manner. This is commonly known as flashing recall signal.

Another feature of the invention is the provision of an improved calling supervisory control circuit whereby the calling supervisory signal associated with the calling end of the link circuit is disabled in response to the association of the connecting circuit with the calling line and is maintained disabled until the called subscriber has answered and replaced his receiver on the switchhook.

Other features will be apparent from the following description and appended claims.

Referring to the drawing, A designates a calling subscriber and M a called subscriber, with a cord circuit C, embodying the present invention, used to interconnect the subscribers' lines for conversation. T partially represents a trunk line to which the cord C may be also connected for extending a call to a distant subscriber at some other exchange. Associated with the cord circuit is a four party selective ringing system.

Assuming that subscriber A wishes to converse with subscriber M, A will signal the central office in the usual manner, whereupon the operator will insert the answering plug of the cord circuit C into the jack associated with A's line, thereupon completing a circuit for the lighting of lamp 2, and the operation of relay 1 which may be traced

from grounded battery through the filament of supervisory lamp 2, relay 1 and thence to ground over the sleeve of the calling line. Relay 1 in operating closes a circuit for relay 3 which can be traced from grounded 60

battery at relay 3, right hand winding of relay 3, normal contacts of listening key 23, middle alternate contacts of relay 1 and thence to ground at the outer left normal contacts of relay 8. Relay 3 thereupon en-

gages in this circuit and in operating closes an obvious circuit for the operation of relay 4. Relay 3 in operating also connects the operator's telephone set across the tip and ring of the cord. This relay now locks up 70

over its left hand inner alternate contact and its left hand winding, normal contacts of listening key 23 through the right hand middle alternate contact of relay 1 and the outer left hand normal contact of relay 8 75

to ground. Relay 4 in operating shunts out and extinguishes lamp 2 in a circuit which can be traced from grounded battery through the filament of lamp 2, right hand winding of relay 4, right hand alternate con-

60 tact of relay 4 and alternate contact of the supervisory relay 7, which operated over an obvious circuit when the plug was inserted in the calling line jack, and thence to grounded battery over the inner left hand alternate contact of relay 4. This circuit also functions as a holding circuit for relay 4 under control of relay 7. The operation of relay 3 also opened at its inner left hand

75 normal contact the battery connection to the relays corresponding to relay 3 in other cord circuits at the same position. This prevents any other cord circuit from being connected to the operator's telephone set and also permits the operator to put up other cord cir-

80 cuits for succeeding calls while she is connected and talking with a calling subscriber. This is called the advance plug-in feature of the cord circuit. The operation of relay 4 also connects ground at its left outer alternate contact to establish an energizing circuit for relay 6 which may be traced from grounded battery, winding of relay 6, inner

85 left hand normal contacts of relay 8 and thence to ground at relay 3 over the left outer alternate contact of relay 8. Relay 6 in operating associates the master ringing equipment with the cord circuit and estab-

90 lishes a circuit for relay 9 which may be traced from ground through the winding of

100 relay 6, inner left hand normal contacts of relay 8 and thence to ground at relay 3 over the left outer alternate contact of relay 8. Relay 6 in operating associates the master ringing equipment with the cord circuit and estab-

110 lishes a circuit for relay 9 which may be traced from ground through the winding of

relay 9, conductor 24, contacts 25 of relay 6, conductor 26, right hand normal contact of relay 8 and thence to grounded battery through the winding of relay 8.

- 5 Relay 9 operates in this circuit and lights the ringing pilot lamp 10 in an obvious circuit. Relay 8 which is in series with relay 9 does not operate, however, due to the high resistance winding of relay 9 which does not permit sufficient current to flow in the circuit for its operation.

In case the calling subscriber does not respond when the operator answers the call due to line or other trouble, the operator can, 15 if desired, leave this line plugged up and disconnect her telephone set from the cord by operating the emergency listening out key 23 individual to this particular cord thereby breaking the locking circuit for relay 3 and 20 permitting it to release. Key 23 locks and remains operated until such time as the operator desires to release it and reconnect her telephone to this particular connection. The release of relay 3 causes the release of relays 25 6 and 9.

The operator is now free to answer other waiting calls.

If, however, the operator receives the desired number from the calling subscriber she 30 plugs the calling end of her cord into the desired line whereupon relay 5 energizes and operates in series with the supervisory lamp 30 over a path which extends from grounded battery through the filament of lamp 30, winding of relay 5 and thence to ground over the sleeve of the called line. Supervisory lamp 30, however, does not light in this circuit as it is shunted through the resistance 35 11 to battery at the outer alternate contact of relay 6. Let it be assumed that the M party on the called line is desired, in which case the master ringing key M would be depressed, thus causing relay 12 to be operated in an obvious circuit. Relay 12 in operating 40 closes a circuit for the operation of relay 14 which can be traced from grounded battery over the outer left hand alternate contacts of relay 4, conductor 52, conductor 36, winding of relay 14, conductor 32, contacts 31 of 45 relay 6 and thence to ground through the inner right hand alternate contacts of relay 12. The operation of relay 12 also causes the operation of relay 8 in an obvious circuit. Relay 8 in operating locks itself up to ground 50 over the contacts of relay 5, which relay remains operated during the time the calling plug is in the jack of the called line. Relay 8 in operating also opens the original operating circuit for relay 6 but closes at its inner left hand alternate contact a holding circuit for relay 6 which can be traced from grounded battery through the winding of relay 6, inner left hand alternate contacts 55 25 of relay 6 and thence to ground through the outermost right hand alternate contacts

of relay 12. In addition relay 8 also opens the operating circuit for relay 3 at its outer left armature, thereby causing the release of relay 3 which relay in releasing disconnects the operator's telephone from the cord and 70 closes a battery circuit to other relays in the position corresponding to relay 3. The operation of relay 12 also causes relay 13 to operate in an obvious circuit. The master ringing key M having caused the operation 75 of relays 8, 13, and 14 can now be released at any time thereby causing the release of relay 12 and the consequent release of relay 6 thereby disconnecting the master ringing circuit from the cord. Upon the operation 80 of relay 14 prior to the release of relay 6 a locking circuit was established for relay 13 which can be traced from grounded battery through the winding of relay 13, its right hand alternate contact, conductor 32, inner 85 lower alternate contact of relay 14, conductor 33, normal contacts of relay 15, conductor 34, conductor 35 and thence to ground through the right hand alternate contacts of relay 5. Relay 14 in operating is also locked in a circuit which can be traced from grounded battery, outer left alternate contacts of relay 4, conductors 52 and 36, winding or relay 14, inner lower alternate contact of relay 14, conductor 33, normal contacts of 90 relay 15, conductor 34, conductor 35 to ground through the alternate contacts of relay 5. Relay 13 in operating, connects at its left hand alternate contact positive pulsating 95 ringing current to the line over a path which may be traced from the current source 60 through the left hand winding of relay 15, normal contacts of relays 16 and 17, conductor 37, lowermost alternate contact of relay 14 100 to the ring side of the cord and line and thence over the line where it will be assumed to cause the operation of the ringer at station M on the called line in a well known manner.

It will be noted that the operation of relay 110 14 provides an auxiliary shunt path to maintain the supervisory lamp dark when the original path was broken by the release of relay 6. This shunt path may now be traced from grounded battery through the upper inner alternate contacts of relay 14 and resistance 11 through the lamp to grounded battery.

Automatic disconnection of ringing on abandoned calls and flashing recall on the answering cord.

In case the calling subscriber should hang up before the called subscriber answers, the 125 following occurs: supervisory relay 7 will release, thereby releasing relay 4 and also breaking the shunt around supervisory lamp 2 and allowing it to become lighted. Relay 4 in releasing opens the circuit for relay 14 130

thereby disconnecting the ringing current from the called line. Relay 14 in releasing opens the locking circuit for relay 13 which relay then releases. The release of relay 14 further removes the shunt from around the calling supervisory lamp 30 which, of course, becomes lighted.

Automatic disconnection of ringing on answered calls.

Assuming that the calling subscriber does not hang up, the automatic ringing will persist until the called subscriber answers, at which time relay 15 will operate in the following circuit: positive pulsating source 60, left alternate contacts of relay 13, left hand winding of relay 15, left normal contacts of relay 16, inner left normal contacts of relay 17, lowermost alternate contacts of relay 14, ring conductors of the cord and line through the subscriber's set, tip conductors of the line and cord, uppermost alternate contacts of relay 14 to ground at the outer left normal contact of relay 17. Relay 15 in energizing opens at its normal contacts the locking circuits for relays 13 and 14, both of which relays release, thereby disconnecting the ringing current from the cord. When the called subscriber answers, and relay 14 releases, it will be noted that the shunt around the calling supervisory lamp 30 is opened at the upper inner alternate contacts of relay 14, but the calling supervisory relay 20 operates immediately over an obvious circuit causing relay 50 to operate over an obvious path thereby again shunting the calling supervisory lamp through grounded battery over the left alternate contacts of relay 50 and through resistance 11.

It will be observed that when both the calling and called subscribers have their receivers off the hook, both the left hand and right hand windings of relay 21 are shunted, the left hand winding being shunted in the following circuit: grounded battery, left hand winding of relay 21, right hand alternate contacts of relay 4, alternate contacts of relay 7, inner left hand alternate contacts of relay 4 to grounded battery, and the right hand winding being shunted in a circuit which can be traced from grounded battery, right hand winding of relay 21 and left hand alternate contacts of relay 50 to grounded battery. Relay 21 being released, the actuation of the emergency listen-in key will not have any effect in connecting the operator's telephone across the cord as the circuit for relay 3 is already broken at the contacts of relay 21 thereby preventing the operator from listening in on a conversation. In case either of the parties hang up, the shunt around either the left or the right hand winding of relay 21 will be removed due to the release of the supervisory relays 7 or 20, as the case may be, thereby allowing

relay 21 to operate over a path which can be traced from grounded battery, left hand winding of relay 21, right hand winding of relay 4, relay 1 and thence to ground on the sleeve of the calling subscriber's line if the calling subscriber has hung up, or over a path which can be traced from grounded battery, right hand winding of relay 21, resistance 11, winding of relay 5 and thence to ground on the sleeve of the called subscriber's line in case the called subscriber has hung up.

If at this time the listening key 22 is operated, a circuit which extends from ground, contacts of relay 21, normal contacts of key 23, right hand winding of relay 3 to grounded battery over the normal contacts of relay 3 will be completed for the operation of relay 3 to connect the operator's telephone across the cord.

Upon the completion of conversation, both subscribers will hang up, causing the release of relays 7 and 20. The release of relay 20 releases relay 50 which removes the shunt from around the calling supervisory lamp which becomes lighted and the release of relay 7 opens the locking circuit for relay 4 which in releasing opens the shunt circuit around supervisory lamp 2, thereby causing it to become lighted. It will therefore be noted that the calling supervisory lamp is not lighted until the called subscriber has answered and hung up. This provides what is known as a dark key shelf feature.

It will be noted that the windings of relay 21 are of a high resistance and will not provide a low enough shunt path to extinguish either of the supervisory lamps.

Let us now assume the condition where the called subscriber either has not answered the ring or has answered and hung up and the calling subscriber desires to recall the operator before the cord circuit is taken down. In the case before described, if the called subscriber does not answer, relays 7, 4, 14 and 13 will be released and supervisory lamps 2 and 30 will be lighted and the ringing current will be disconnected from the called line when the calling subscriber replaces his receiver on the hook. These same relays will release and both lamps will be lighted when a conversation is completed and both receivers are hung up. Now should the calling subscriber desire to recall the operator before the cord circuit is taken down, he will again remove his receiver from the hook thereby causing relay 7 to be again operated which will complete a periodically interrupted shunt circuit around supervisory lamp 2 which can be traced from grounded battery, through interrupter 18, left inner normal contacts of relay 4, alternate contacts of relay 7, right normal contacts of relay 4, resistance 19 and to the upper terminal of supervisory lamp 2 thereby

causing this lamp to flash in step with the interrupter 18 and give the operator what is known as a flashing recall signal.

If the operator wishes to extend a call to some distant operator in response to a toll order by the subscriber A, she will plug the calling end of her cord into trunk circuit T whereupon an energizing circuit is established which operates relay 5 over a path extending from grounded battery, filament of lamp 30, winding of relay 5 and thence to ground over the sleeve of the trunk line. It will be noted that lamp 30 does not light in this circuit as it is shunted through resistance 11 to grounded battery at the outermost right hand alternate contacts of relay 6.

When the operator plugs into the trunk line, she depresses the non-ring key NR whereupon an obvious circuit for relay 40 is established. Relay 40 now energizes and in operating closes its right hand alternate contacts thereby establishing a circuit for relay 8 which can be traced from ground, right hand alternate contacts of relay 40, contacts 25 of relay 6, conductor 26, normal contacts of relay 8 and thence to grounded battery through the winding of relay 8. The operation of relay 40 also causes relay 17 to energize and operate in a circuit which can be traced from ground, left hand alternate contacts of relay 40, contacts 51 of relay 6, winding of relay 17, conductor 53, conductor 52 and thence to grounded battery over the outer left alternate contacts of relay 4. Relay 17 in operating closes its inner right hand alternate contacts thereby locking itself over a path extending from grounded battery at relay 4, left outer alternate contacts of relay 4, conductor 52, conductor 53, winding of relay 17, inner right hand contacts of relay 17, conductor 54, normal contacts of relay 50, conductor 55 and thence to ground through the right hand alternate contacts of relay 5. Relay 8 in operating closes its right hand alternate contacts to form a locking circuit for itself which extends from grounded battery, winding of relay 8, right hand alternate contact of relay 8, conductor 35, and thence to ground over the right hand alternate contacts of relay 5 which relay remains operated during the time the calling plug is inserted in the jack of the trunk line. Relay 8 in operating also closes its inner left hand alternate contacts to establish a holding circuit for relay 6 which can be traced from grounded battery, winding of relay 6, inner left hand alternate contacts of relay 8, contacts 25 of relay 6 and thence to ground through contacts of relay 40. Relay 8 also breaks its outer left hand normal contacts thereby causing the release of relay 3 which, in releasing, disconnects the operator's telephone set from the cord circuit. When the

non-ringing key NR is released ground is disconnected from the circuit for relay 40 as previously traced and therefore deenergizes relays 40 and 6. It will be noted that relay 17 operates and keeps the lamp 30 shunted when relay 6 releases. Relay 6 in releasing obviously disassociates the master ringing key from the cord circuit. When the called subscriber at the distant end answers, relay 20 energizes over an obvious circuit and in operating closes an obvious circuit for relay 50 to cause that relay to operate. Relay 50 in operating opens the previously traced circuit for relay 17 thereby causing that relay to release. However, the operation of relay 50 holds lamp 30 shunted over an obvious circuit, even though relay 17 releases thereby maintaining a dark key shelf until the distant called subscriber has answered and hung up.

What is claimed is:

1. A telephone system comprising telephone lines, an operator's link circuit, a supervisory signal therein, means for shunting said signal responsive to the connection of said link circuit to a calling one of said lines, and means for maintaining said signal shunted until a substation on a called one of said lines has responded and subsequently hangs up.

2. In a telephone system, a cord circuit for interconnecting a calling and a called subscriber's line, a called supervisory signal, a ringing control relay for applying ringing current to the called line, a called supervisory relay, and means including said ringing control relay and said supervisory relay for maintaining said called supervisory signal unoperated until the called subscriber has answered and hung up.

3. In a telephone system, a cord circuit for interconnecting a calling and a called subscriber's line, a called supervisory signal for said called line, a master ringing circuit control relay, a ringing control relay for applying said ringing current to the called line, and a called supervisory relay, said relays successively acting during the establishment of a connection between said calling and said called line to prevent said supervisory signal from being operated until the called subscriber has answered and replaced his receiver on the switchhook.

4. A telephone system comprising lines, a link circuit, means for applying ringing current to a called one of said lines, a supervisory signal, and means successively responsive to the connection of said link circuit to a calling one of said lines, to the operation of said ringing means and to the removal of the receiver at a station on said called line for continuously disabling said signal until the receiver at said called station is replaced on the switch hook.

5. A telephone system comprising lines,

- an operator's link circuit, a supervisory signal, means responsive to the connection of said link circuit with a calling one of said lines to disable said signal, ringing 5 means for signaling a substation on a called one of said lines, means adapted to maintain said signal disabled during the period said called substation is being rung and until the receiver thereat is removed from the 10 hook, and a supervisory relay in said link circuit for further maintaining said signal disabled until the receiver at the called substation is replaced on the hook.
6. A telephone system comprising telephone lines, an operator's link circuit, a supervisory signal associated with the calling end of said link circuit, a master ringing circuit arrangement for signaling on a called one of said lines, and means including a 15 relay operated when said link circuit is connected with a calling one of said lines to associate said master ringing circuit with said link circuit and to disable said supervisory signal.
- 20 7. A telephone system including a calling and a called line, a link circuit for interconnecting said lines, a supervisory signal, a ringing key circuit, means operable upon the connection of said link circuit with a calling one of said lines for associating said ringing key circuit with said link circuit and for disabling said supervisory signal, and other means including a ringing control relay and a supervisory relay for maintaining said signal disabled until the subscriber on a called one of said lines has 25 answered and hung up.
8. In a telephone system, in combination, a calling and a called line, a link circuit 30 for interconnecting said lines, a master ringing circuit and a ringing control relay for applying ringing current to the called line, a supervisory signal associated with the answering end of said cord circuit, means controlled by the replacement and subsequent removal of the calling subscriber's receiver to cause disconnection of said ringing current from the called line and to cause said supervisory signal to be intermittently flashed, a supervisory relay and a second supervisory signal associated with the calling end of said cord circuit, means operable upon the connection of said cord circuit with said calling line to associate said master ringing circuit with said cord circuit and to shunt said second supervisory signal, and means successively controlled by said ringing control relay and said supervisory relay to maintain said supervisory signal shunted until said called subscriber responds and 40 subsequently hangs up.
9. In a telephone system, in combination a calling and a called subscriber's line, a cord circuit for interconnecting said lines, a master ringing circuit arrangement for 45 signaling on the called line, answering and calling supervisory signals associated with the cord circuit, means including a relay for associating said master ringing circuit with said cord circuit and for disabling the calling supervisory signal when said cord circuit is connected with said calling line, means including a second relay operable in response to actuation of said master ringing arrangement to apply ringing current, determined by said master arrangement, to said called line when the calling end of said cord circuit is associated therewith and to continue the disablement of said calling supervisory signal while ringing continues, and other means responsive to replacement of the calling subscriber's receiver before the called subscriber answers to cause disconnection of said ringing current and removal of said disabling condition from said calling 55 supervisory signal.
- In witness whereof, I hereunto subscribe my name this 28th day of April A. D., 1924.
- RICHARD C. DAVIS.
